UNITED STATES PATENT OFFICE.

LAWRENCE F. DULLIGAN, OF GRIFFIN, GEORGIA.

METHOD FOR TREATING TERRY CLOTH OR PILE FABRICS.

Application filed October 7, 1925. Serial No. 61,036.

This invention relates to a new and improved method for treating terry or pile fabrics to produce an upstanding pile or nap thereon.

5 Objects of the invention are to provide treatment for terry cloth or pile fabrics so that the pile assumes an upstanding position; to provide means for treating a cloth having a thin or sparse pile, whereby a uniform, full and upstanding pile is produced; and to provide means for conveying cloth between brushes rotating at a speed differing from the speed of the cloth so that the pile is picked up and left in an upright position.

10 Other objects of the invention will be manifest from the detailed description and claim appended hereto. One practical embodiment of the invention is illustrated in 15 the accompanying drawing forming a part of the specification in which,

The figure is a diagrammatic showing of the various steps involved in the treatment of the cloth according to my invention.

20 As illustrated the numerals 1 and 2 designate a pair of engaging mangle or wringer rolls mounted on shafts 3 and 4 respectively rotatable in opposite directions and imparting a corresponding rotating movement to 25 said rolls. The numerals 5 and 6 designate a pair of brushes, rotatable on the shafts 7 and 8 respectively, said shafts being adapted to rotate in opposite directions. Terry cloth or other fabric 9, having a pile or nap 30 is adapted to be fed to the rolls 1 and 2, whereupon the said cloth leaves the rolls at a speed corresponding to the speed of said rolls. The cloth after leaving the rolls 1 and 2 is conveyed between the brushes 5 and 35 6 at the speed imparted to it by said rolls, suitable yielding take up means (not shown) being provided to maintain the cloth taut. Preferably the brushes 3 have a rotating speed somewhat faster than the speed of the 40 rolls 1.

The operation of the device is as follows: The cloth or fabric 5 after being thoroughly washed preparatory to drying and shipment is run through the wringer rolls 1 and 45 2 where part of the water therein is expelled. The cloth is then usually allowed to dry before being bolted and shipped. In the case 50 of pile cloth, which is commonly used for

Turkish towelling, the pressure of the rolls compresses the cloth and flattens the pile in 55 a manner to make the cloth appear inferior in quality. By conveying the cloth between the brushes as above described, subsequent to the passage through the wringer rolls, with the brushes moving in a direction opposite the lay of the flattened pile the pile is 60 picked up by the bristles of the brushes, due to the fact that the speed of the brushes is faster than the speed of the cloth so that a full, uniform and upstanding pile is produced. The cloth is then allowed to dry, 65 whereby the condition of the cloth after leaving the brushes is rendered relatively permanent.

It frequently happens that cloth or fabrics adapted to have a rich and uniform pile or nap come from the loom with the pile unevenly and imperfectly formed. To straighten out and untangle the pile or nap of the cloth has heretofore been too laborious 70 an operation to render it feasible so that the cloth is disposed of as an inferior product at a great loss. By conveying such cloth between the rotating brushes above described, the pile is straightened and untangled with 75 little labor and with such facility that large quantities of cloth considered inferior in quality are rendered salable.

I claim:

The method of treating terry cloth, suitable for toweling or the like, which comprises passing the cloth in a dampened condition between oppositely rotating rolls, whereby excess moisture is removed and the pile upon either side is given a lay in a direction opposite to the movement of the cloth, then passing the cloth between rotating brushes the portions of which, that contact with the surface of the cloth, are moving in the same direction as the cloth, but faster than the same, whereby the relative movement between the brushes and the cloth is in a direction opposite to the lay of the pile so that an upstanding uniform pile is produced upon either side of the cloth, while 95 it is still damp, and thereafter completing the drying of the cloth.

Signed by me at Griffin, Ga., this Sept. 8 day of 1925.

LAWRENCE F. DULLIGAN.
